UNITED STATES PATENT OFFICE.

ALLEN P. WILSON, OF WALTHAM, MASSACHUSETTS, ASSIGNOR TO BOSTON PENCIL
POINTER COMPANY, OF WALTHAM, MASSACHUSETTS, A CORPORATION OF
MASSACHUSETTS.

PENCIL-POINTER.

1,249,579.

Specification of Letters Patent. Patented Dec. 11, 1917.

Application filed November 6, 1913. Serial No. 799,588.

To all whom it may concern:

Be it known that I, ALLEN P. WILSON, a citizen of the United States, residing at Waltham, in the county of Middlesex and State of Massachusetts, have invented certain new and useful Improvements in Pencil-Pointers; and I do hereby declare the following specification, taken in connection with the accompanying drawings, forming a part of the same, to be a full, clear, and exact description thereof.

The invention relates to pencil pointers and has for its object to produce a pencil-pointer which will remove the wood from the lead in such a manner as to expose more of the lead and thereby produce a point which will wear longer and require less frequent sharpening than the points now produced.

20 To these ends the invention consists in the novel combination and arrangement of parts hereinafter described and more particularly set forth in the claims.

In describing the invention in detail, reference will be had to the accompanying drawings, in which—

Figure 1 is a side elevation of my novel pencil pointer.

Fig. 2 is a top plan view of the cutter-carrier.

Fig. 3 is a front end view of the cutter-carrier.

Fig. 4 is a sectional view on line $x-x$, Fig. 1.

Fig. 5 is a side view of a pencil showing the character of point produced by the improved pointer.

Referring to the drawings 1 represents the standard of the machine, which is provided with a suitable foot-portion 2 by means of which it may be secured to a suitable support. The standard 1 has formed integral therewith a head portion 3 and an elongated bearing 4 for the shaft of the cutter-carrier.

45 The head-portion 3 is recessed and is provided with a series of internal gear-teeth 5, as shown in Fig. 4. The cutter-carrier 6 is provided at one end with a shaft 7 which is journaled in the elongated bearing 4 and 50 is provided at one end with a handle 8 by means of which the cutter-carrier is revolved and at the other end is provided with a tubular pencil guiding portion 9 into which the pencil is inserted while it is being sharpened. The cutter-carrier is open at its center

portion and two rotary cutters 10 having spiral cutter-blades are mounted upon spindles 11 to rotate in said open center portion and are provided at one end with gears 12, which are arranged to mesh with the internal gear-teeth 5 in the head portion.

Said rotary cutters 10 are arranged at both a horizontal and a vertical incline to the longitudinal axis of the cutter-carrier and also to the longitudinal axis of the pencil-guide 9, as shown in Fig. 3, and this double canting or inclining of the rotary cutters in both a vertical and horizontal direction causes said cutters to operate upon the pencil in such a manner as to remove more of the wood and expose a longer pointed lead than is the case when said cutters are canted or inclined in only one direction as heretofore.

It will be seen that the amount of wood removed and the amount of lead exposed during the sharpening of the pencil can be varied by varying the amount of the double incline of the rotary cutters, and it has been found that with the cutters inclined both horizontally and vertically approximately as shown in Fig. 3, a point will be produced substantially as shown in Fig. 5 and with the exposed lead substantially one-third longer than would be the case if the cutters were inclined in only one direction.

It will also be seen that this increase in the length of the lead will enable the pencil to be used for a longer time before it becomes necessary to resharpen the same, and that thus the wear on the pencil pointer will be greatly diminished and its efficiency and usefulness correspondingly lengthened.

What I claim as my invention and desire to secure by Letters Patent is:

1. In a pencil sharpening machine or the like, a rotatably mounted cutter-carrier and a cutter mounted therein, said cutter having its axis arranged longitudinally and in the general direction of the axis of the cutter-carrier, and so disposed as to have no plane in common to the axis of said cutter-carrier.

2. In a pencil sharpening machine or the like, a rotatably mounted cutter-carrier and two rotary cutters mounted therein, each of said cutters having its axis arranged longitudinally and in the general direction of the axis of said cutter-carrier, and having no plane in common to the axis of said carrier.

3. In a pencil sharpening machine or the like, a rotatably mounted cutter-carrier and two cylindrical rotary cutters mounted therein and provided with spiral cutting edges, each of said cutters having its axis arranged longitudinally and in the general direction of the axis of said cutter-carrier and having no plane in common to the axis of said cutter-carrier.
- 10 4. In a pencil sharpening machine or the like, a rotatably mounted cutter-carrier and a rotary cutter mounted therein comprising a base and a curved surface of revolution with the cutting portion located wholly on said curved surface of revolution, and having its axis of revolution so disposed as to have no plane in common to the axis of said cutter-carrier.
- 15 5. In a pencil sharpening machine or the like, a rotatably mounted cutter-carrier and two rotary cutters mounted therein, each of

said cutters comprising a base and a curved surface of revolution, with the cutting portion located wholly on said curved surface of revolution, and having its axis of revolution so disposed as to have no plane in common to the axis of the other of said cutters. 25

6. In a pencil sharpening machine or the like, a rotatably mounted cutter-carrier and two rotary cutters mounted therein, each of 30 said cutters comprising a base and a curved surface of revolution, with the cutter located wholly on said curved surface of revolution, and having its axis of revolution so disposed as to have no plane in common to 35 the axis of said carrier and the axis of the other of said cutters.

ALLEN P. WILSON.
